INVENTOR.

UNITED STATES PATENT OFFICE.

MAX HERSKOVITZ, OF CHICAGO, ILLINOIS.

PICTURE-FRAME.

SPECIFICATION forming part of Letters Patent No. 605,821, dated June 14, 1898.

Application filed December 27, 1897. Serial No. 663,736. (No model.)

To all whom it may concern:

Be it known that I, MAX HERSKOVITZ, a citizen of the United States, residing at Chicago, in the county of Cook, State of Illinois, have 5 invented a new and useful Improvement in Glass Picture-Frames, of which the following is a specification.

My invention is related to the pressed-glass and earthenware industries as an article of manufacture; and the object of my improvement is to provide a better method of fixing the picture, glass, and backing to the frame. The present method of gluing or sliding them in grooves is unsatisfactory and insecure. I 15 attain these objects by a mechanism illustrated in the accompanying drawings, in which—

Figure 1 is a front view of a frame with picture fixed in it. Fig. 2 is a back view of the 20 entire frame with a portion of the binding-ring B cut away. Fig. 3 is a side view, partly in vertical section, cut at A, showing all parts of the frame.

Similar letters refer to similar parts throughout the several views.

The circular rim a, Fig. 3, formed at a right angle to the plane of the frame, is provided with lugs a' at suitable distances apart on the outside. Between the lugs small perforations 30 a², Fig. 2, are made in the rim horizontal with the plane of the frame. An annular ring B of metal, provided with a flange turned inwardly at a right angle to the plane of the frame, is formed, the ring being large enough 35 to fit outside and over the rim a. Grooves b are swaged outwardly in the sides of the ring, inclining slightly from the plane of the ring, provided with openings on the lower edge of the ring. The grooves are situated at distances to correspond with the lugs on the rim 40 of the frame.

The glass C is placed in the rabbet. The picture c is then laid on the glass, and the backing D is then fitted in the rim. The binding-ring is then placed over the rim, with the openings in the grooves b opposite to the lugs a', and is then pressed down until the lugs will enter the inclining portion of the grooves, as shown at a', Fig. 3. Then by turning the binding-ring to the right or left, as the case may 45 be, the contents of the frame will be closely pressed together. When in this position, apertures b' are made in the ring opposite to the apertures a² in the rim to receive pins f. The pin f is an ordinary brass binding-pin, 50 such as is used in fastening legal papers together, having two legs. The pin f is put through the apertures in the ring and through the aperture in the rim a². The legs of the pin are then bent to the right and left, as shown 55 in Fig. 2. The object of the pins f is to prevent the ring from working loose.

I do not wish to confine myself to a circular frame exclusively, as the same binding device may be used on a square frame, as the 60 binding frame or ring with inclining grooves may be moved longitudinally onto lugs and secured by pins f to the rim of square frame.

Having described my invention, what I wish 65 to secure by Letters Patent is—

As an article of manufacture, the combination in a glass frame of the rim a, having lugs on the outside and horizontal apertures; the binding-ring B provided with inclining grooves b, adapted to engage the said lugs; 70 the perforations in said ring adapted to receive the pins; the pins f adapted to fix the ring to the frame; substantially as described.

MAX HERSKOVITZ.
